UNITED STATES PATENT OFFICE.

ARTHUR EDGCUMBE RENDLE, OF PHILADELPHIA, PENNSYLVANIA, ASSIGNOR TO
KEYSTONE TYPE FOUNDRY, OF PHILADELPHIA, PENNSYLVANIA, A CORPORA-
TION OF PENNSYLVANIA.

METAL WINDOW-SASH.

1,303,113.

Specification of Letters Patent.

Patented May 6, 1919.

Application filed June 5, 1917. Serial No. 173,060.

To all whom it may concern:

Be it known that I, ARTHUR E. RENDLE, a citizen of Great Britain, residing at Philadelphia, Philadelphia county, and State of Pennsylvania, have invented and discovered 5 certain new and useful Improvements in Metal Window-Sashes, of which the following is a specification.

My said invention relates to a method of 10 making and assembling the component parts of metal frame structures, and to the structure thereof *per se*, and consists in the novel steps of procedure of manufacture and combinations and arrangements of parts in the 15 structure hereinafter described and particularly set forth in the accompanying claims.

The purpose of the invention is to produce 20 a substantially jointless metal frame structure which will be free from attack by rust, corrosion, or other deterioration, due to the 25 elements; one wherein the parts of the structure may be assembled in an easy manner, and in which the completed structure will possess the strength requisite for its purpose.

25 The invention is designed with special reference to window frame structures, to the end that the windows, when located in places inaccessible for painting, will not rust, and thereby avoid the expense which such painting entails and the extreme danger attending work of this character.

30 A window or sash that is made of rolled steel or cast iron, unless kept frequently painted, rusts and corrodes when exposed to the weather or air. It is invariably the case 35 that many of the steel windows in a building of modern construction are inaccessible from the outside without extreme danger, and consequently it is difficult to paint the exterior 40 of these windows, with the result that they are often left unpainted, and in a remarkably short time will rust and deteriorate.

45 To overcome the above mentioned disadvantages, and also to save the heavy expense of this painting and avoid the danger as well, it is proposed to cover the outside or exposed 50 surfaces of the sashes or windows with a non-rustable sheathing. And it is further contemplated to unite the elements of the frame, through the medium of the sheathing, in such a manner as to obtain a virtually jointless structure.

The invention is disclosed by way of illus-

tration in the accompanying drawings, wherein:

55

Figure 1 is a front elevation of a window sash.

Fig. 2, a vertical sectional view thereof on the line 2—2 of Fig. 1.

Fig. 3, a horizontal sectional view on the 60 line 3—3 of Fig. 1, and

Fig. 4, an enlarged detail view, showing the manner of applying the sheathing.

Referring to the construction in detail, and with like reference characters indicating 65 corresponding parts, 5 designates the outside frame of the sash, constructed of any suitable angle-iron; 6 are the vertical muntins of T or I iron shapes; and 7 the horizontal pieces completing the inner parts of the 70 frame structure.

The frame may be provided with the usual swinging section, or ventilator, comprising a rectangular frame 8, pivotally mounted on the muntins 6, as at 9; and 75 angle-irons 10 and 11 are secured to said swinging section and one of the crosspieces 7, and, with the crossbars 12 and 13, provide the means for holding the swinging section, when closed, within the plane of the 80 frame. Also, the two strips or bars 14 are carried by said swinging section along the sides of the lower or outwardly swinging portion of said section.

85 The frame 5, muntins 6, and crosspieces 7 are covered with a sheathing 15, of metal, that is applied thereto either by drawing, bending, or in any other preferred manner. Likewise, the exposed portions or flanges of 90 the bars 12, 13 and 14 of the swinging window sections are covered with this sheathing, which is applied thereto as in the manner stated.

95 It will, therefore, be seen that all of the outer or exposed portions of the steel frame, or window, thus covered by this sheathing will be protected against rust, corrosion, or other deterioration due to the elements. And it will be obvious that this addition to the metal framework will rather augment 100 the strength of the structure and add to its attractiveness, inasmuch as it is proposed to cover all those portions of the structure that are exposed.

105 The parts of the window or sash are assembled in a simple and novel manner, to

wit, the outer frame 5 has the sheathing 15 applied thereto at the sides, top, and bottom in the manner stated. The flanges of the muntins are covered with the sheet metal, 5 and in like manner the horizontal T's and I's; and on each part the strip overlies the bar continuously for its entire length. The vertical muntins are perforated with apertures having cross-sections agreeing with the 10 structure of horizontal parts of the frame to be received, and are then placed on a flat surface, preferably a large table or bench. The horizontal bars are then driven through these apertures and the whole inner frame 15 secured to the outside frame of the sash by riveting or welding. The exterior steel of the structure is now entirely covered with a non-rusting sheet metal, and without a joint or seam, except at the ventilators; and in 20 this respect applicant has accomplished what has heretofore not been possible with steel structures having mitered or other joints, which prevent the same from being covered in the manner he proposes, and, in like manner, with frames made where the horizontal pieces lie flush with the muntins, it is impossible to cover the bars with a continuous 25 strip of metal.

It is obvious that those skilled in the art 30 may vary the details of construction and arrangement of parts without departing from the spirit of my invention, and I, therefore, do not wish to be limited to such details except as may be required by the claims.

35 Having thus fully described my said invention, what I claim as new and desire to secure by Letters Patent is:

1. A rust-proof frame structure comprising 40 a plurality of parallel metal members, strips of sheathing covering said members respectively for the length thereof, said sheathed members having perforations, a second plurality of members, non-rustable metal strips on said second members, and

Copies of this patent may be obtained for five cents each, by addressing the "Commissioner of Patents, Washington, D. C."

said second named members passing through 45 the apertures of the first named sheathed members and secured thereto, said sheathing providing an unbroken surface throughout the frame, substantially as set forth.

2. A rust-proof window frame structure 50 comprising an outer frame, a sheathing of non-rustable material on said frame, a plurality of muntins secured to said frame, sheaths of non-rustable metal on said muntins, said sheathed muntins provided with 55 perforations; a plurality of horizontal members, sheaths of non-rustable metal covering said horizontal members, and said sheathed horizontal members passing through the apertures of the sheathed muntins and secured to said outer frame, said sheathing providing an unbroken surface throughout the frame, substantially as set forth. 60

3. A rust-proof window frame structure 65 comprising an outer angle-iron frame portion, a plurality of angle-iron muntins secured to said outer frame, sheathing of non-rustable metal on said muntins for the entire length thereof, said sheathed muntins provided with aligned perforations respectively; a plurality of horizontal members of angle-iron construction, sheathing of non-rustable metal on said horizontal members for the entire length thereof, and said sheathed horizontal members passing 70 through the apertures of the sheathed muntins and secured thereto, said sheathing providing an unbroken surface throughout the frame, substantially as set forth. 75

In witness whereof I have hereunto set my 80 hand and seal at Philadelphia, Pennsylvania, this 4th day of June, A. D. nineteen hundred and seventeen.

ARTHUR EDGCUMBE RENDLE. [L. S.]
